WILLIAM GRIFFITH, JR., OF POTTSVILLE, PENNSYLVANIA, ASSIGNOR TO HIMSELF,
JOSEPH S. PATTERSON, AND THOMAS C. ZULICK, OF SAME PLACE.

Letters Patent No. 94,306, dated August 31, 1869.

IMPROVED FURNACE FOR PRODUCING IRON DIRECT FROM THE ORE.

The Schedule referred to in these Letters Patent and making part of the same.

To all whom it may concern:

Be it known that I, WILLIAM GRIFFITH, Jr., of Pottsville, in the county of Schuylkill, and State of Pennsylvania, have invented a new and improved Direct Iron-Producing Furnace; and I do hereby declare that the following is a full, clear, and exact description thereof, which will enable others skilled in the art to make and use the same, reference being had to the accompanying drawing, forming part of this specification, in which—

Figure 1 represents a vertical longitudinal section of my improved direct iron-producing furnace, the plane of section being indicated by the line *xx*, fig. 3.

Figure 2 is a vertical transverse section of the same.

Figure 3 is a plan or top view, partly in section, of the same, the plane of section being indicated by the line *yy*, fig. 1.

Similar letters of reference indicate corresponding parts.

This invention relates to a new furnace for reducing and producing iron directly from the ore, by a continuous operation, and has, for its object, to reduce the expense of, and to economize fuel and time during the operation.

The invention consists chiefly in arranging a deoxidizing-chamber above the welding or puddling-furnace, said chamber being heated by the gases that escape from the fire in the said furnace. The deoxidizing-chamber contains a number of retorts, in which the ore is exposed to the action of the heat, together with anthracite-coal dust that is all wasted at present in the anthracite-regions, and other carbonaceous matter. The number of retorts is such that the action can be divided into three or more terms, so that when the ore in one set of retorts is ready to be fed into the welding or puddling-furnace, that in the second set will be about in the middle of the deoxidizing-process, which, in the third set, will have but just commenced.

The invention also consists in the peculiar construction of the retorts, which are made of conical form, and which are moulded of clay, so as to be stronger and less thick than the retorts built of fire-brick, heretofore used.

The invention also consists in putting a steam-generator into the smoke-passage between the retorts, to utilize all surplus heat of the gases of combustion, for the purpose of supplying the fire in the furnace with steam to aid combustion.

The invention finally consists in the arrangement and combination, with the welding-furnace and retort-chamber, of a funnel or trough, for guiding the ore from the retorts into the furnace. The lower ends of the retorts communicate with said funnel, and are closed by sliding or other gates. The lower end of the funnel is closed by a sliding or swinging door, which separates it from the welding-chamber. When

the contents of a retort are to be transferred to the welding-bed, the lower door of the funnel is first opened, and then the slide of the desired retort. The contents of the retort will then flow through the funnel into the welding-bed, to be there exposed directly to the gases of the furnace, and to the requisite manipulation.

A, in the drawing, represents a welding or puddling-furnace of ordinary or suitable construction, in which *a* is the fore-chamber, *b* the welding-chamber, *c* the chimney, and *d* the cold-air chamber under the welding-bed, all arranged in the well-known, or in any suitable manner.

The chimney *c* leads from the furnace *A* into a chamber, *B*, arranged directly above the furnace, and conducts all the products of combustion into the said chamber *B*.

In the chamber, which is supported on walls or posts, *C*, some distance above the furnace *A*, is arranged a series of vertical retorts, *D* *D*, of oval cross-section, as shown.

These retorts are made conical, so that they are about three times larger at the lower than they are at the upper ends, and are made of cement, graphite, or clay, or any other refractory material, moulded into the requisite form.

Retorts for similar purposes were heretofore generally built of fire-brick, which made them thick, and occupied much room, and at all times contained more than one charge. Mine only holds one charge for the furnace, which makes the iron uniform.

My moulded retorts can be made thin, because they are small, compared with other retorts for such purposes, and will thereby not only occupy less room, but will let the heat strike through much quicker, thereby obtaining quicker action on the ore.

The upper ends of the retorts are fitted through horizontal plates or ribs, *f*, formed in the chamber *B*, as shown in fig. 2.

Their lower ends are closed by means of sliding or swinging gates *E* *E*, one such slide or gate being provided for each retort, as shown in fig. 1.

F is a horizontal metallic cylinder, fitted into the upper part of the chamber *B*, between the ribs *f*, or otherwise. It is to be filled with water, which will be evaporated by the heat of the gases passing through the chamber *B*.

The steam thus produced is, in a pipe, *g*, carried to the fire-chamber of the furnace, to facilitate the combustion.

The retorts, of which I prefer to have about eighteen or twenty-four in the chamber *B*, are so placed that they can be entirely enveloped in the gases carried into the chamber through the chimney.

The gases, after having traversed the chamber *B*, pass off through a smoke-stack, *G*.

H is an iron or other funnel, interposed between the

furnace A and chamber B, so that its large open part embraces and communicates with the lower ends of all retorts, while its contracted lower end connects with an opening, h, in the top of the welding-chamber b.

This opening, h, can be closed by a suitable gate or slide, I.

The crushed ore to be reduced is put into the retorts, together with waste anthracite-coal dust, or other equivalent material. It is then reduced and, more mechanically than chemically, combined with the dust.

When sufficiently deoxidized, the ore is let into the furnace, by opening the gates I and E, and is therein acted on by the gases, to become treated in the desired manner.

The welding-chamber has suitable openings or working-holes.

The retorts are made conical, so that the ore will not be clogged in them.

Having thus described my invention,

What I claim as new, and desire to secure by Letters Patent, is—

1. The deoxidizing-chamber B, containing the retorts D D, when arranged above or in connection with a welding-furnace, substantially as described, so that the retorts will be heated by the gases escaping from the welding-furnace, as described.

2. The retorts D D, when made substantially as described, of conical form, and moulded, as specified.

3. The steam-generator F, when arranged within the deoxidizing-chamber, to supply steam to the firebox, as set forth.

4. The funnel H, when arranged in combination with the furnace A, having the cap or valve I, and with the retorts D, having the movable bottoms E, all arranged, combined, and operating substantially as herein shown and described.
